UNITED STATES PATENT OFFICE

THEODORE ENSEL, OF PERU, INDIANA

HEATER

Application filed December 6, 1928. Serial No. 324,280.

This invention relates to improvements in heating attachments for gas stoves and the like.

The primary object of this invention is the provision of an improved attachment adapted to be used with gas stoves and the like, by means of which a plurality of vessels or utensils may be readily heated from the heat produced by a single gas burner or the like, for the purpose of economically utilizing the maximum amount of heat for cooking.

A further object of this invention is the provision of an improved heater attachment for gas ranges and the like, which includes improved means for directly heating a utensil above a gas burner and laterally deflecting the heat in a novel relation to another location where an auxiliary vessel is placed.

20 A further and important object of this invention is the provision of an improved heater attachment for gas ranges, embodying improved means for support against vessels of various sizes.

25 Other objects and advantages of this invention will be apparent during the course of the following detailed description.

In the accompanying drawings, forming a part of this specification, and wherein similar reference characters designate corresponding parts throughout the several views.

Figure 1 is a longitudinal sectional view taken through the improved attachment, 35 taken substantially on the line 1—1 of Figure 2.

Figure 2 is a plan view of the improved attachment.

40 Figure 3 is a fragmentary perspective view showing cooperating lid or cover details for supporting a plurality of vessels of different sizes upon an opening of the attachment.

In the drawings, wherein for the purpose of illustration is shown only a preferred embodiment of the invention, the letter A may generally designate the attachment, which comprises a housing B having means C for supporting thereon a plurality of vessels or utensils of different sizes, directly over a burner D; the device furthermore including

a grate E for receiving vessels of various sizes in an efficient relation for proper heating.

The housing B is of novel construction, including a top wall structure 10 provided with peripherally depending side and end walls 11 conforming to the shape thereof, and depending in a plane at right angles to the top wall. The top wall 10 includes the wall portion 11 at one end thereof, which is provided with an opening 12 wherein the adjustable lid structure C detachably fits in a novel relation for supporting vessels or utensils of different sizes. The wall 11 is connected with a wall portion 13 forming part of the top wall 10 by means of a transverse sloping wall portion 15, which extends upwardly from the plane of the wall portion 11 in order to offset the wall portion 13 in a plane above the wall portion 11. The wall portion 13 has the grate E either detachably or integrally disposed thereon as a part thereof. The depending walls 11 preferably follow the contour of the top wall, preferably in the form of the numeral 8, and below the top wall a compartment is provided. A bottom wall 16 is disposed in an imperforate relation below the wall portion 13 of the top wall structure, terminating in a straight line 18 at a location below the sloping top wall portion 15, just where the latter joins the top wall portion 11 above described. The housing B when resting on the wall 16 supports the housing so that the wall portions 11 and 13 are horizontally disposed, with the opening in the bottom wall, placed over the burner D, in order that heat from the latter may enter the compartment below the wall portion 11, and after heating the vessel, such as shown at F supported thereon, the residue heat passes into the housing between the wall portion 13 and the bottom wall 16, for heating the vessel or utensil H supported on the grate E.

Referring to the cover structure C, the same includes outer and inner ring-shaped sections 30 and 31 respectively. The wall 11 of the housing B is provided with an under flange 33 about the opening 12, below the plane of the top surface of the wall, adapted to marginally support the ring-shaped cover 100

section 30. This ring-shaped cover section 30 has an opening 34 therein which is eccentrically positioned therein with respect to the radius from which the outer circumference of the section 30 is formed. On the under surface of the cover section 30 is disposed a deflecting flange 36, best shown in Figures 1 and 2 of the drawing, but also shown in Figure 3, which is segmental in form, and extends about the opening 34 of the section 30, preferably concentric therewith, for slightly over 180°, and has the ends 37 and 38 relatively spaced and extending in the direction of the offset portion 15 of the top wall of the housing. The purpose of the flange 36 is to maintain the heat from the burner D about the opening 34, and to deflect the same therefrom laterally into the space below the grate E for heating the auxiliary utensil H. In order that the section 30 will always assume this position, it is preferred to provide a notch or opening 39 in the supporting flange 33, wherein a depending lug 40 on the bottom of the lid or cover section 30 is adapted to seat, in the relation shown in the drawings.

The inner ring-shaped cover section 31 is adapted to seat in the opening 34 of the cover section 30, and to this end the cover section 30 is provided with an annular supporting flange 42, below the plane of the top surface of the cover section 30, whereon the outer marginal portion of the ring-shaped cover section 31 seats, to position the top surface of the cover sections 30 and 31 flush with each other, and with the top surface of the housing wall portion 11, as shown in Figure 1. The cover section 31 is provided with an opening 45 therein, eccentric to the circumference of the outer periphery of said cover section 31. On the under surface of the cover section 31, concentrically about the opening 45, is disposed a heat deflecting flange 49, which extends for over 180° about the opening 45, and at its ends 50 and 51 are directed towards the grate E of the housing, for the purpose of maintaining the heat about the opening 45 and deflecting the same therefrom into the space in the housing B beneath the grate E. To insure that the lid section 31 seats in proper manner, the same is provided with a depending lug 55, which is adapted to seat within a suitable notch 56 provided in the flange 42 which supports said section in the section 30, as shown in the drawings.

With respect to the grate E, the housing top wall portion 13 is provided with a downwardly converging heat deflecting flange 60, which extends downwardly into the space above the housing bottom wall 16, and which is provided with preferably integral bars 62 extending radially inward from the inner restricted periphery 63 thereof, and which join in a central portion 64. The bars 62 are offset upwardly intermediate their ends to provide a sort of table of said bars adjacent to

where they connect at 64, the plane of which is normally below the plane of the wall portion 13 above mentioned. If desired, reinforcing and article supporting ribs 67 extend contiguous or in alignment with the radial bars 62, in raised relation over the heat deflecting flange 60 and partially extending in a raised relation over the top surface of the wall portion 13 surrounding the deflecting flange 60. On these ribs 67 the utensil H is adapted to seat, and, of course, the utensil will be spaced slightly above the wall portion 13 to permit of a circulation of the heat along the housing B longitudinally thereof, due to the fact that these ribs prevent the utensil or vessel from seating in a closed relation over the opening upon which the grate E is disposed. The convergency of the ribs 67 permits the vessel H to be accurately heated in event it is less in diameter than the outer circumference of the deflecting flange 60.

From the foregoing description of this invention it is apparent that an improved attachment for economically utilizing heat from gas ranges has been provided, by means of which a plurality of utensils may be heated at the same time, and entirely independent of the size of the utensils, within reasonable limits. The heat will be efficiently deflected from the housing above the burner D laterally, without waste of heat, inasmuch as the cover sections 30 and 31 are impervious and the utensil F is adapted to be supported over the opening in the attachment, so as to close the same from escape of heat at this location. The heat is deflected laterally by means of either the flanges 36 or 49, as the case may be, and passes into the larger compartment below the grate E; the heat passing thru the housing below this grate being deflected centrally by the downwardly convergent flange 60, and efficiently directed by the bottom 16 against the utensil H, in a manner which is apparent.

Various changes in the shape, size, and arrangement of parts may be made to the form of invention herein shown and described, without departing from the spirit of the invention or the scope of the claims.

I claim:

1. A heating attachment for gas stoves and the like, comprising a relatively flat hollow body having a low portion at one end with a heat receiving opening in the bottom thereof and having a high portion at its other end opening in to the low portion and into which heat may expand from the low portion, said portions each having utensil receiving openings in their top walls, and a series of consecutively nested opening reducing rings fitting in the utensil opening of the low portion, each of said rings having a depending heat deflecting flange opening toward the high portion of the body to deflect the heat directly from the bottom of the utensil on the

low portion into the high portion irrespective of the size of the utensil opening.

2. A heating attachment for gas stoves and the like, comprising a relatively flat hollow body having a low portion at one end with a heat receiving opening in the bottom thereof and having a high portion at its other end opening into the low portion and into which heat may expand from the low portion, said portions each having utensil receiving openings in their top walls, and a series of consecutively reduced rings for the utensil opening of the low portion, the inner marginal edges of the top wall of the low portion and of the rings having depressed marginal seats to receive the outer marginal edges of the adjacent reduced rings to support the same, and each ring also having a depending semi-circular flange opening at one side of the ring toward the high portion of the body for deflecting heat rising through the low portion of the body into the high portion thereof.

3. A heating attachment for gas stoves and the like, comprising a relatively flat hollow body having a low portion at one end with a heat receiving opening in the bottom thereof and having a high portion at its other end opening into the low portion and into which heat may expand from the low portion, said portions each having utensil receiving openings in their top walls, and a series of consecutively reduced rings for the utensil opening of the low portion, the inner marginal edges of the top wall of the low portion and of the rings having depressed marginal seats to receive the outer marginal edges of the adjacent reduced rings to support the same, and each ring also having a depending semi-circular flange opening at one side of the ring toward the high portion of the body for deflecting heat rising through the low portion of the body into the high portion thereof, each of said depressed seats having a notch therein and each ring having a lug adapted to engage in the respective notch to determine and hold the rings with their heat deflecting flanges in proper relation to the high portion of the body and insure the passage of the heat to the latter.

4. In a heating attachment for stoves the combination of a top wall structure including a high wall portion and a low wall portion at an elevation below the high wall portion, each of the high and low wall portions having openings therein over which utensils are adapted to be supported, said top wall structure having a depending peripheral skirt entirely thereabout, a bottom wall connected with the lower margin of the skirt only beneath the higher wall portion of said top wall structure so as to provide a restricted passageway from the space beneath the low wall portion to the space beneath the high wall portion, and an annular downwardly con-

vergent heat deflecting flange surrounding the opening in the higher wall portion and providing a restricted opening at the lower margin thereof.
